United States Patent Office

Des. 195,728
Patented July 23, 1963

195,728

MIXING IMPELLER

Lawrence I. Freedman and John W. Tone, Wilmington,
Del., assignors to Ronson Corporation, Woodbridge,
N.J., a corporation of New Jersey

Filed Mar. 21, 1962, Ser. No. 69,365

Term of patent 14 years

(Cl. D44—1)

Fig. 1.

Fig. 2.

Fig. 3.

Fig. 4.

FIG. 1 is a top plan view of a mixing impeller showing our new design;

FIG. 2 is a front elevational view;

FIG. 3 is a top perspective view, a portion of the shaft being broken away for convenience of illustration; and

FIG. 4 is a bottom perspective view, a portion of the shaft being broken away for convenience of illustration.

We claim:

The ornamental design for a mixing impeller, as shown.
